United States Patent Office

Des. 233,767
Patented Nov. 26, 1974

233,767

CIGARETTE LIGHTER

Hermann Schlamp, Ehrenstrasse 25-27, 5000
Cologne 1, Germany

Filed Feb. 26, 1974, Ser. No. 445,884

Claims priority, application Germany Sept. 3, 1973

Term of patent 14 years

Int. Cl. D27—05

U.S. Cl. D27—42 R

FIG. 1

FIG. 2

FIG. 3

FIG. 4

FIG. 5

FIG. 6

FIG. 1 is a perspective view of a cigarette lighter embodying my new design;

FIG. 2 is an end elevation;

FIG. 3 is a side elevation, the other side looking essentially the same;

FIG. 4 is an end elevation of the opposite side of FIG. 2;

FIG. 5 is a bottom plan view; and

FIG. 6 is a top plan view.

I claim:

The ornamental design for a cigarette lighter, as shown.
